[57] **CLAIM**

The ornamental design for fur headphones, as shown
and described.

DESCRIPTION

FIG. 1 is a top, front and right side perspective view of
a fur head phone showing my new design;

FIG. 2 is a left side elevational view thereof; and

FIG. 3 is a bottom plan view thereof.

The electrical wire and connector are broken away for
ease of illustration.

FIG. 2

FIG. 3
